RETRIEVABLE WELL PUMP

Arthur G. Gage, Bell, Calif.

Application April 24, 1950, Serial No. 157,735

17 Claims. (Cl. 103—46)

1

This invention relates to improvements in well pumping systems of the type employing a pump submersible in the well fluid and so associated with two pipe strings running from the pump to the ground surface, as to be operable by fluid pressure communicated through one of the strings, to deliver the well production through the other string.

More particularly, the invention is directed to such systems in which the pump is adapted to be run down to seating or operating position within one of the pipe strings (preferably the inner of two strings one of which is contained in the other), and from which the pump is retrievable as by elevation on a wire line.

The invention is concerned primarily with the removability of the pump for repair, inspection or replacement, and the pressure conditioning of the pumping system in a manner facilitating and assuring safe recovery of the pump. Specifically the invention has for its major object the equalization, or near equalization of hydraulic pressures applied to the pump, so as to permit its initial unseating and removal from the well on a wire line with only the pump load required to be carried by the line.

As illustrative, the invention will be described as embodied in a pumping system employing inner and outer pipe strings, within the former of which the pump is run down to seating position. Further as illustrative, the pump may be adapted for operation by fluid pressure communicated through the inner string, the actuating fluid discharge and the production fluid being delivered up through the space between the two strings. Normally, upward displacement of the pump from seated position within a lower barrel extension of the inner string is resisted by the hydraulic pressure therein above the pump, which is greater than any effective pressure acting upwardly against the pump below its seat. Accordingly, in the absence of provision for balancing the hydraulic pressures applied downwardly and upwardly against the pump, removal of the pump on a wire line would require overcoming the differential of those pressures and imposition of unsafe loads on the wire line, at least until the pump is unseated.

In accordance with the invention, provision is made for equalizing the pressures tending to seat and unseat the pump, by the simple expedient of controlled communication to the underside of the pump by way of one of the hydraulic columns, and without requiring movement

2

of either pipe string, of pressure sufficient to balance the pressure tending to seat the pump. The resulting pressure balance then reduces the pump unseating load on the retrieving wire line to the safe weight of the pump.

All the various objects of the invention, as well as the details of certain illustrative embodiments, will be fully understood from the following description of the systems illustrated by the accompanying drawing, in which:

Fig. 1 is a general view illustrating the pumping system, including the pipe string and pump assembly, and the flow lines at the ground surface; and

Fig. 2 is a fragmentary enlargement of the dual string and barrel assembly at the location of the pump.

The well pipe assembly comprises a diagrammatically illustrated outer pipe string 10 extending from the ground surface down to the production depth in the well and carrying seat 11 engageable by the pump barrel as will later appear. Below the seat, the outer string has a production oil inlet 12, down flow through which normally is closed by a check valve 13 contained within a cage 14 seatable downwardly within the recess 15.

The inner string 16, contained within and in spaced relation to the outer string 10, carries and may be regarded as including a pump barrel 17 which normally seats downwardly against the seat 11 as illustrated in Fig. 1. The barrel 17 has a lower extension 17a which receives the well fluid entering chamber 18 through openings 19. The barrel extension 17a has a suitable loose connection, such as a bolt 20, with the check valve cage 14, so that upon elevation of the inner string, the cage and valve are lifted from their seats as shown in Fig. 2.

The inner string 16 carries a fluid pressure actuated pump 21 which may be of any of the usual types of construction operable by fluid pressure communicated from the ground surface through the inner string and taken into the pump through its inlet 22, to receive well fluid through the lower end 21a of the pump, and discharge the combined actuating and production fluids through outlets 122 and the barrel port 23 into the space 24 between the pipe strings. The pump is shown generally to comprise a fluid driven motor section 50 which operates by way of rod 51 the vertically reciprocating tubular or liquid passing plunger 52 carrying check valve 152, so that on its up stroke the plunger displaces well fluid taken into the pump body and plunger past check valve 152, together with the motor operat-

ing fluid exhausted at 53, through ports 122 and 23 into the column in space 24.

Thus normally, the inner string 16 contains an inner actuating fluid column extending from above the pump to the ground surface, and space 24 between the strings contains an outer column of the production and exhausted actuating fluids being pumped to the ground surface. The pump is adapted to be lowered within string 16 on a wire line 25 to operating position in which the pump is rested on the barrel seat 26. Fluid leakage between the pump and barrel may be prevented by suitable packing or seal rings 27 contained within recesses in the barrel and engaged against the pump surface. The pump is shown to carry a projection 28 releasably engageable by any suitable tool or overshot 29 carried by the wire line 25. The tool is shown typically to comprise a pair of crossed arms 55 pivoted at 56 for engagement with the projection 28, and releasable therefrom as by a go-devil 57 dropped on the wire line 25.

For purposes of normal operation, assume the pump to have been lowered to the seated position shown in Fig. 1, with the wire line removed. Actuating fluid is delivered to the pump through the inner hydraulic column from a suitable pressure source such as line 30 leading from a pump 31 and connecting with the pipe string below a normally closed gate 32. Production fluid is delivered through the outer column and line 33 to reservoir 34 or other disposal. During normal operation valves 35 and 36 in lines 30 and 33 are open, and valves 37 and 38 in lines 39 and 40 are closed.

As will be understood, at such time as it may be desired to remove the pump from the well for purposes of inspection, repair or replacement, elevation of the pump from its seat 26 is resisted by the weight of the liquid column contained within the pipe string 16 above the pump, or the differential between the pressure applied to the pump by that column weight and the lesser pressure exerted upwardly against the lower end of the pump below its seat. Accordingly, in undertaking to remove the pump on the wire line, the latter must assume the column load or pressure differential at least until the pump is unseated, in the absence of an initial balancing of the pressures applied to the pump above and below its seat. In accordance with the invention, provision is made for effecting the balancing of such pressures by the transmission from the ground surface, and typically pump 31, of abnormally high pressures by way of either of the fluid columns contained within the string 16 or space 24 between the strings.

As best illustrated in Fig. 2, the pump barrel 17 may contain a passage 41 leading from a location above the pump or the upper seal 27, to the lower interior of the barrel below the pump seat 26. Passage 41 includes an enlarged bore 42 containing a check valve 43 normally seated by coil spring 44 having such resistance to opening of the valve that the latter will remain seated at all normal operating pressures of the inner fluid column in string 16. At such time as it may be desirable to balance the pressures acting downwardly and upwardly against the pump, valves 36, 37 and 38 may be closed and pump 31 operated to build up within string 16 and passage 41 a pressure sufficient to unseat the check valve 43, whereupon corresponding pressure is communicated to barrel 17a, chamber 18 and the underside of the pump. Using a gate type fitting

32 capable of closing the string 16 above line 30, and capable also of pressure sealing about the line 25, the latter may be run down for attachment to the pump. With the pressure against the latter balanced, the only load imposed on the wire line for unseating an elevation of the pump, is only the weight of the pump itself.

As an alternative to the described means for balancing pressures on the pump through communication of pressure by way of the inner fluid column, provision also may be made for balancing the pressures by the communication of abnormally high fluid pressure from the column in space 24 to the underside of the pump. For this purpose I may provide in the seat 11 a passage 46 normally closed by check valve 47 seated upwardly by coil spring 48. Normally, spring 48 maintains the check valve 47 seated to prevent fluid flow from the outer column into chamber 18. By closing valves 35 and 36 with valve 37 opened, pump 31 may operate to increase the outer fluid column pressure to a degree sufficient to unseat the valve 27 and communicate to chamber 18 and the pump housing 17a a pressure sufficient to at least balance the fluid load on the top of the pump, and to facilitate its removal on the wire line in the manner previously explained. In view of the fact that any desired pressure may be thus communicated from the outer column to the underside of the pump, it becomes possible to so exceed the hydrostatic load on the pump as to permit displacement or pumping of the pump up through string 16, to the exclusion of elevation by the wire line.

At such time as may be desirable to remove the inner string 16 from the well, the string may be raised to unseat the pump barrel from seat 11 as in the condition of Fig. 2, whereupon the inner fluid column drains through the pump into the outer column, and the latter in turn may restore to the normal well liquid level since elevation of the string opens the bottom check valve 13.

I claim:

1. The combination comprising a well pipe string, a pump seat carried by the lower portion of said string, a pump adapted to be lowered within said string into engagement with said seat and operable by fluid pressure communicated from the top of the well to pump fluid out of the well, upward displacement of the pump from said seat normally being resisted by the pressure of a liquid column extending above the pump seat within said string to the top of the well and applied to an upwardly facing area of the pump, means within the well forming a passage adapted while the pump remains seated to communicate from a lower portion of said column to a downwardly facing area of the pump fluid pressure communicated from the top of the well through said column and sufficiently great to at least substantially equal the fluid pressure applied to said upwardly facing area of the pump, and valve means in the well continuously closing said passage to fluid flow therethrough during normal operation of the pump.

2. The combination comprising a well pipe string, a pump seat carried by the lower portion of said string, a pump adapted to be lowered within said string into engagement with said seat and operable by fluid pressure communicated from the top of the well to pump fluid out of the well, upward displacement of the pump from said seat normally being resisted by the pressure

of a liquid column extending above the pump seat within said string to the top of the well and applied to an upwardly facing area of the pump, means within the well forming a passage adapted while the pump remains seated to communicate from a lower portion of said column to a downwardly facing area of the pump fluid pressure communicated from the top of the well through said column and sufficiently great to at least substantially equal the fluid pressure applied to said upwardly facing area of the pump, and a fluid pressure responsive valve in the well continuously closing said passage to fluid flow therethrough during normal operation of the well.

3. The combination comprising a well pipe string, a pump seat carried by the lower portion of said string, a pump adapted to be lowered within said string into engagement with said seat and operable by fluid pressure communicated from the top of the well to pump fluid out of the well, upward displacement of the pump from said seat normally being resisted by the pressure of a liquid column extending above the pump seat to the top of the well and applied to an upwardly facing area of the pump above said seat, means forming a passage adapted while the pump remains seated to apply to a downwardly facing area of the pump below said seat fluid pressure communicated from the top of the well and sufficiently great to at least substantially equal the fluid pressure applied to said upwardly facing area of the pump, and valve means in the well closing off said communication of fluid pressure to said downwardly facing area of the pump through said passage during normal operation of the pump.

4. The combination comprising a well pipe string, a pump seat carried by the lower portion of said string, a pump adapted to be lowered within said string into engagement with said seat and operable by fluid pressure communicated from the top of the well to pump fluid out of the well, upward displacement of the pump from said seat normally being resisted by the pressure of a liquid column extending above the pump seat to the top of the well and applied to an upwardly facing area of the pump above said seat, means forming a passage through which fluid pressure communicated from the top of the well by way of said liquid column is applicable to a downwardly facing area of the pump below said seat and to a degree sufficient to at least substantially equalize the pressures against said upwardly and downwardly facing area of the pump, a spring-urged check valve normally closing fluid flow through said passage and operable to open in response to predetermined increase of the pump operating fluid pressure to communicate that increased pressure to said downwardly facing area of the pump.

5. The combination comprising a well pipe string, a pump barrel carried by said string and containing a seat, a pump adapted to be lowered within said string onto said seat and operable by fluid pressure communicated from the top of the well by way of a liquid column in said string to pump fluid out of the well, upward displacement of the pump from said seat normally being resisted by the pressure of said column applied to an upwardly facing area of the pump, means forming in the wall of said barrel a passage through which increased pressure of said column communicated therethrough from the top of the well is applicable to a downwardly

facing area of the pump to a degree sufficient to at least substantially equalize the pressure against said areas, and a fluid pressure responsive valve controlling the fluid flow through said passage.

6. The combination comprising a well pipe string, a pump barrel carried by said string and containing a seat, a pump adapted to be lowered within said string onto said seat and operable by fluid pressure communicated from the top of the well by way of a liquid column in said string to pump fluid out of the well, upward displacement of the pump from said seat normally being resisted by the pressure of said column applied to an upwardly facing area of the pump, means forming in the wall of said barrel a passage through which increased pressure of said column is transmitted within the barrel from above said seat to below the seat and is applicable to a downwardly facing area of the pump to a degree sufficient to at least substantially equalize the pressure against said areas, a fluid pressure responsive valve controlling the fluid flow through said passage, and means carried by the pump for attachment to a wire line lowered in said pipe string to elevate the pump therein to the ground surface.

7. The combination comprising two spaced pipe strings lowered in a well one inside the other and containing inner and outer fluid columns, a seat within the lower portion of the outer string and a shoulder in the inner string normally engaged downwardly against said seat, said inner string including a pump barrel containing a pump seat, a pump adapted to be lowered within the inner string onto said pump seat and operable by fluid pressure communicated from the top of the well by way of said inner fluid column to pump well fluid into said outer fluid column and to the ground surface, there being a fluid passage through which one of said columns is communicable with the barrel below said pump seat, and a valve in said passage closing such communication at normal column operating pressures and operable to establish such communication by the transmission from the top of the well of abnormally high pressure by way of said one of the columns, and thereby at least substantially equalize the pressures acting downwardly and upwardly against the pump.

8. The combination comprising two spaced pipe strings lowered in a well one inside the other and containing inner and outer fluid columns, a seat within the lower portion of the outer string and a shoulder in the inner string normally engaged downwardly against said seat, said inner string including a pump barrel containing a pump seat, a pump adapted to be lowered within the inner string onto said pump seat and operable by fluid pressure communicated from the top of the well by way of said inner fluid column to pump well fluid into said outer fluid column and to the ground surface, there being a fluid passage through which one of said columns is communicable with the barrel below said pump seat, and a valve in said passage closing such communication at normal column operating pressures and operable to establish such communication by the transmission from the top of the well of abnormally high pressure by way of said one of the columns, and thereby at least substantially equalize the pressures acting downwardly and upwardly against the pump, and means carried by the pump for attachment to a

wire line lowered in the inner pipe string to elevate the pump to the ground surface.

9. The combination comprising two spaced pipe strings lowered in a well one inside the other and containing inner and outer fluid columns, a seat within the lower portion of the outer string and a shoulder on the inner string normally engaged downwardly against said seat, said inner string including a pump barrel containing a pump seat, a pump adapted to be lowered within the inner string onto said pump seat and operable by fluid pressure communicated from the top of the well by way of said inner fluid column to pump well fluid into said outer fluid column and to the ground surface, there being a fluid passage through which the inner fluid column is communicable with the barrel below said pump seat, and a valve in said passage closing such communication at normal column operating pressures and operable to establish such communication by the transmission from the top of the well of abnormally high pressure by way of said inner column, and thereby at least substantially equalize the pressures acting downwardly and upwardly against the pump.

10. The combination comprising two spaced pipe strings lowered in a well one inside the other and containing inner and outer fluid columns, a seat within the lower portion of the outer string and a shoulder on the inner string normally engaged downwardly against said seat, said inner string including a pump barrel containing a pump seat, a pump adapted to be lowered within the inner string onto said pump seat and operable by fluid pressure communicated from the top of the well by way of said inner fluid column to pump well fluid into said outer fluid column and to the ground surface, there being a fluid passage through which the outer fluid column is communicable with the barrel below said pump seat, and a valve in said passage closing such communication at normal column operating pressures and operable to establish such communication by the transmission from the top of the well of abnormally high pressure by way of said outer column, and thereby at least substantially equalize the pressures acting downwardly and upwardly against the pump.

11. The combination comprising two spaced pipe strings lowered in a well one inside the other and containing inner and outer fluid columns, a seat within the lower portion of the outer string and a shoulder on the inner string normally engaged downwardly against said seat, said inner string including a pump barrel containing a pump seat, a pump adapted to be lowered within the inner string onto said pump seat and operable by fluid pressure communicated from the top of the well by way of said inner fluid column to pump well fluid into said outer fluid column and to the ground surface, there being a fluid passage in the wall of said barrel extending between locations above and below the pump seat to communicate the inner column pressure to the under side of the pump, and a spring-urged check valve in said passage closing such communication at normal inner column operating pressures and operable to establish such communication by the transmission from the top of the well of abnormally high pressure by way of the inner column and thereby at least substantially equalize the pressures acting downwardly and upwardly against the pump.

12. The combination comprising two spaced pipe strings lowered in a well one inside the

other and containing inner and outer fluid columns, a seat within the lower portion of the outer string and a shoulder on the inner string normally engaged downwardly against said seat, said inner string including a pump barrel containing a pump seat, a pump adapted to be lowered within the inner string onto said pump seat and operable by fluid pressure communicated from the top of the well by way of said inner fluid column to pump well fluid into said outer fluid column and to the ground surface, there being a fluid passage extending through the first mentioned seat to communicate the outer column pressure to the under side of the pump, and a spring-urged check valve in said passage closing such communication as normal outer column operating pressures and operable to establish such communication by the transmission from the top of the well of abnormally high pressures by way of the outer column, and thereby at least substantially equalize the pressures acting downwardly and upwardly against the pump.

13. The combination comprising two spaced pipe strings lowered in a well one inside the other and containing inner and outer fluid columns, an upwardly opening check valve closing fluid escape from a chamber in bottom of the outer pipe string directly above said chamber, a pump barrel included in the inner pipe string and seating downwardly against said seat, a pump seat within and carried by said barrel, a pump adapted to be lowered within the inner string onto said pump seat and operable by fluid pressure communicated from the top of the well by way of said inner fluid column to pump well fluid from said chamber into said outer fluid column and to the ground surface, a vertically reciprocable piston within the pump, a bottom check valve carried by the pump, and a connection between the inner pipe string and the first mentioned check valve whereby the latter may be opened by elevation of the inner string to drain fluid from said chambers into the wells.

14. The combination comprising a first pipe string extending vertically within a well and containing a vertically extended liquid column, a second pipe string extending vertically within the well and disposed around said first string and containing another vertically extended liquid column at the outside of and extending substantially entirely about said first string, a pump seat carried by the lower portion of said string, a pump adapted to be lowered within said first string into engagement with said seat and operable by fluid pressure communicated from the top of the well through one of said columns to pump fluid out of the well by way of the other column, upward displacement of the pump from said seat normally being resisted by the pressure of one of said columns applied to an upwardly facing area of the pump, means within the well forming a passage adapted while the pump remains seated to communicate from a lower portion of the first of said columns to a downwardly facing area of the pump fluid pressure communicated from the top of the well by way of said first column and sufficiently great to at least substantially equal the fluid pressure applied to said upwardly facing area of the pump, and valve means in the well continuously closing said passage to fluid flow therethrough during normal operation of the pump.

15. A combination as recited in claim 14, and in which said valve means comprise a spring-urged check valve operable to open in response

to predetermined increase in the pressure of said first column to communicate that increased pressure to said downwardly facing area of the pump.

16. A combination as recited in claim 15, and in which said pump operating pressure is communicated through said first column.

17. A combination as recited in claim 14, and including means carried by the pump for attachment to a wire line lowered in said string to elevate the pump therein to the ground surface. 10
